UNITED STATES PATENT OFFICE.

THEODORE M. MACOMBER, OF BINGHAMTON, NEW YORK.

DESIGN FOR A VEHICLE-RUNNER.

46,031.

Specification for Design.

Patented June 30, 1914.

Application filed April 17, 1913. Serial No. 761,854. Term of patent 14 years.

To all whom it may concern:

Be it known that I, THEODORE M. MACOMBER, a citizen of the United States of America, residing on Rural Free Delivery Route No. 4, in the city of Binghamton, county of Broome, and State of New York, have invented a new, original, and ornamental Design for Vehicle-Runners, of which the following is a specification, reference being had to the accompanying drawing, forming part thereof.

Figure 1 is a side elevation of a buggy, equipped with my invention; Fig. 2 is an edge view of the runner detached.

I claim:

The ornamental design for a vehicle runner, as shown.

THEODORE M. MACOMBER.
